UNITED STATES PATENT OFFICE.

WALTER F. KEENAN, JR., OF NEW YORK, N. Y., ASSIGNOR TO POWER SPECIALTY COMPANY, OF NEW YORK, N. Y., A CORPORATION OF NEW YORK.

SUPERHEATER FOR MARINE BOILERS.

1,282,850.

Specification of Letters Patent. Patented Oct. 29, 1918.

Application filed April 20, 1917. Serial No. 163,351.

To all whom it may concern:

Be it known that I, WALTER F. KEENAN, Jr., a citizen of the United States, residing at New York, in the county and State of New York, have invented certain new and useful Improvements in Superheaters for Marine Boilers, of which the following is a full, clear and exact description.

The present invention relates to superheaters designed more particularly for marine boilers, but applicable generally to other types, and is an improvement in the manner of placing or installing the superheater and of supporting it in position where it will receive the proper degree of heat from the gases of combustion.

According to the invention, the superheater, preferably one of the now well-known Foster type, is located in the path of the gases from the boiler tubes to the smoke stack, and extends across substantially the whole of such space so that its surface secures the maximum contact with the hot gases without interfering to an appreciable or objectionable extent with the furnace itself.

To support the superheater in this relation to the furnace and boiler, a plate is secured by bolts in brackets in the side of the uptake next to the boiler tube sheet and formed with a series of inclined slots or openings through which the rear bends of the superheater tubes or elements project and by which they are firmly supported. At the other end the ends of the tubes pass through holes in a plate or other suitable support, and all of these ends are properly joined to the headers and connections which are contained in a box or chamber alongside the uptake and to which access may be readily had, when necessary, for inspection or repair.

In the drawing hereto annexed the details of construction of the improvement are illustrated.

Figure 1 is a part longitudinal section of a boiler equipped with the superheater.

Fig. 2 is a part end view and section of the boiler.

Fig. 3 is an enlarged detail of the means for supporting the superheater elements in the slotted plate; and

Fig. 4 is an enlarged view of a portion of said plate.

The boiler preferably of the marine type

is or may be of any construction desired, provided it has or is adapted to be provided with a passageway from the tubes to the smoke stack, suitable for the reception of the superheater in the manner hereinafter described. In the drawings this boiler is indicated by A, the tubes by B, and the passage-way for the escape of gas or the uptake flue by C.

In the latter above the bank of tubes are brackets D, secured to the wall of the uptake, and to these brackets by means of bolts E passing through angle plates F secured to plates G, the said plates are secured in position. As shown in Fig. 4, the plates G contain slots or inclined openings H.

The tubes K of the superheaters at their front ends pass through holes in the front wall of the uptake or through a plate I, secured over an opening therein and are united to headers M or to cross-connections N to make up the superheater in the usual manner, while the rear bends of the tubes are passed through the openings in the plate G.

Around the headers a chamber O is formed and it will be understood that this as well as other parts of the walls are provided with doors or other similar means of gaining access to the superheater and the uptake.

Should it become necessary, for instance, to replace any superheater element, the bolts E are removed and the superheater element having been disconnected at the rear, may be withdrawn from plate G, which by the removal of the bolts, may be forced back to permit of this.

It will be observed that the superheater extends across the entire uptake, so that there will be a maximum absorption of heat, but the space occupied by the superheater tubes is not sufficient to interfere with or impair the furnace draft.

What I claim is:—

1. The combination with a steam boiler of the form described, of a superheater located in the flue space between the boiler tubes and the smoke stack, having spaced straight tubes extending across the space in the line of its greater dimension and occupying substantially the whole passageway for hot gases, a perforated plate secured to and near the rear wall of such space, through which the bends of the superheater tubes extend and by which they are supported, and a

front wall plate at the opposite side of the space through which the ends of the tubes extend.

2. The combination with a steam boiler of
5 the form described, of a superheater located
in the flue space between the boiler tubes and
the smoke stack, having spaced straight
tubes extending across the space in the line
of its greater dimension and occupying sub-
10 stantially the whole passage-way for hot
gases, brackets secured to the rear wall of

the flue space, a plate removably secured thereto, containing perforations through which the bends of the superheater extend so as to be supported and protected from the 15 direct action of the hot gases by said plate, and a plate fixed to the front wall through which the ends of the tubes extend to the headers and connections.

In testimony whereof I hereunto affix my 20
signature.

WALTER F. KEENAN, Jr.

Certificate of Correction.

It is hereby certified that in Letters Patent No. 1,282,850, granted October 29, 1918, upon the application of Walter F. Keenan, jr., of New York, N. Y., for an improvement in "Superheaters for Marine Boilers," an error appears in the printed specification requiring correction as follows: Page 2, line 2, claim 1, strike out the article "the", second occurrence; and that the said Letters Patent should be read with this correction therein that the same may conform to the record of the case in the Patent Office.

Signed and sealed this 7th day of November, A. D., 1922.

[~~SEAL.~~]

KARL FENNING,

Acting Commissioner of Patents.
